(57) **CLAIM**

The ornamental design for a container for kitchen machine, as shown and described.

DESCRIPTION

FIG. 1 is a perspective view of a container for kitchen machine showing my ornamental design; and

FIG. 2 is a top view of the container for kitchen machine embodiment shown in FIG. 1; and

FIG. 3 is a bottom view of the container for kitchen machine embodiment shown in FIG. 1; and

FIG. 4 is a left view of the container for kitchen machine embodiment shown in FIG. 1; and

FIG. 5 is a rear view of the container for kitchen machine embodiment shown in FIG. 1; and

FIG. 6 is a right view of the container for kitchen machine embodiment shown in FIG. 1; and,

FIG. 7 is a front view of the container for kitchen machine embodiment shown in FIG. 1.
